[57] CLAIM

The ornamental design for a student desk, as shown and described.

DESCRIPTION

FIG. 1 is a front elevational view of a student desk showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front elevational view in extended position;

FIG. 8 is a rear elevational view thereof;

FIG. 9 is a left side elevational view thereof;

FIG. 10 is a right side elevational view thereof;

FIG. 11 is a top plan view thereof;

FIG. 12 is a bottom plan view thereof; and,

FIG. 13 is a perspective view with the top storage door open for convenience of illustration; the broken line showing of students and chairs form no part of the claimed design.
